DESIGN FOR A TYPEWRITER

Samuel A. Thompson, New York, N. Y., assignor
to Simplex Typewriter Company, Inc., New
York, N. Y.

Application October 1, 1947, Serial No. 141,699

Term of patent 7 years

(Cl. D64—11)

To all whom it may concern:

Be it known that I, Samuel A. Thompson, a citizen of the United States and a resident of the city, county, and State of New York, have invented a new, original, and ornamental Design for a Typewriter, of which the following is a specification, reference being had to the accompanying drawing, forming part thereof, in which—

Fig. 1 is a plan view of a typewriter showing my new design; and

Fig. 2 is a side elevational view thereof.

I claim:

The ornamental design for a typewriter, as shown.

SAMUEL A. THOMPSON.
